APPARATUS FOR BURNING LIQUID FUELS

Milton A. Powers and John A. Wilson, Detroit,
Mich., assignors, by mesne assignments, to The
Timken-Detroit Axle Company, a corporation
of Ohio

Application October 2, 1934, Serial No. 746,582

14 Claims.

(Cl. 158—4)

The present invention relates to methods of and apparatus for burning liquid fuels. More particularly the present invention relates to methods of, and apparatus for igniting and combusting liquid fuels in burners of the wall flame type, whereby such burners are enabled to function reliably and economically while using fuel oil of poorer quality and higher viscosity than has heretofore been thought possible of use.

5 In co-pending Powers application for a "Metal hearth ring", application No. 620,373, dated July 1, 1932, and Wilson application No. 682,374, dated July 27, 1933 for a Grill, will be found a full description of the operation and characteristics of 10 an oil burner having a metal hearth ring construction in comparison with the conventional refractory clay segments heretofore universally used. Further investigation has disclosed that the use of such metal constructions in specialized forms, and in accordance with the methods 15 of combustion of our invention which are about to be formulated, opens heretofore unsuspected possibilities in the effective burning of lower quality oils with the wall flame burner. During 20 the first few years of use of the wall flame burner, and in fact until only comparatively recently, it was considered impractical to recommend oils inferior in quality to the No. 1 grade (United States Commercial Standards) for reliable domestic use 25 in automatic burners of this type. Later developments in ignition devices and segment form enabled the same burners to operate with the better commercial grades of No. 2 oil. The recent rapid introduction of the metal segment construction 30 disclosed in our previously mentioned applications has warranted the recommendation of even the poorest grades of No. 2 oil without qualification. In fact good grades of No. 3 oil are burned with complete satisfaction in numerous installations. 35 Continued development in the laboratory with poor grades of both No. 3 and No. 4 oil gives indications of fair success with the No. 3 but almost hopeless results with the low quality No. 4 oil. An analysis of the difficulties proved that 40 an entirely different angle of attack was necessary for a successful outcome and the following line of reasoning was responsible for the success attained by the fuel burning methods and constructions of our invention to be described later.

45 In the first place let us briefly analyze the modus operandi of the present day wall flame burner. Oil is thrown by centrifugal forces from the distributor head to the flame or combustion rim at the periphery of the boiler. The most important requirement is that this oil be divided

5 into sufficiently small droplets to wet the hearth periphery evenly. To attempt to atomize the oil or to break it into particles smaller than sufficient to meet this requirement is distinctly undesirable as finely atomized oil will burn rapidly in the presence of air and difficulty will be encountered in holding the flame at the periphery. Under conditions of excessive atomization the rate of flame propagation toward the distributor 10 will exceed the outward velocity of the oil and the flame will accordingly burn or "flash" back to the distributor causing trouble. The first requirement, therefore, is to wet the flame rim with liquid oil. There will be sufficient splatter resulting from the oil striking the face of the segment 15 to propagate the ignition flame around the periphery. Thereafter the wet oil is vaporized by the heat in the flame ring segments received from the burning oil, the vapors are mixed with the outflowing air stream and combustion occurs. At normal operating temperature the rate 20 of vapor production is so high that the flame is unable to maintain itself in the immediate vicinity of the vaporizing oil and "rises" to the top of the segment where it burns in suspension over 25 the metal segments, around the grills, (if grills are used in the installation) and in close proximity to the boiler wall.

It is therefore evident that the vaporizing zone or region is filled with rich vapors and no flame 30 can exist, because very little if any air or oxygen is present. Hence a "reducing" atmosphere, as contrasted with an "oxidizing" atmosphere is present in this zone. Consequently (except for a short time in starting and after stopping) no conditions exist in the oil impinging zone for removing the oil and its residue from the flame ring except the heat of vaporization.

35 The specification for a No. 1 oil calls for a distillation range, with all of the oil evaporated, at 40 a temperature not to exceed 600° F. A flame rim segment temperature of this degree or higher is accordingly all that is necessary to completely change all of the liquid oil to a vapor. The rigid specifications, as to free carbon, ash, sulphur, and 45 so on practically assures their absence from fuels of No. 1 specification now on the market. Hence operation may continue indefinitely without accumulation of carbon or foreign matter while using No. 1 oil—and continued good combustion 50 will result. These are the conditions under which a burner of the character shown by the previously mentioned applications will operate with high quality, sediment free oils.

The next poorer grade oil, a No. 2 presents 55

a somewhat different story. The distillation requirements specify that 90 percent of the oil must vaporize below 620° F. In other words a somewhat higher temperature is needed to vaporize even the lighter nine tenths of the oil, but there is no specific limitation as to the vaporizing range of the last 10 percent of the oil. It is assumed, of course, that said remainder would continue in conformity with the quality of the first 5 10 15 20 25 30 35 40 45 50 55 60 65 70 75 80 85 90 95 100 105 110 115 120 125 130 135 140 145 in a boiler having a base portion 10 and a water section 11.

Mounted on an inwardly extending flange 12 of base 10, is a hearth member 13 which consists of a refractory clay mass which may be molded in place in the boiler. Extending through a centrally disposed aperture in hearth 13 is a liquid fuel and air distributor assembly, comprising a stand 14, a motor 15, and a distributor head 16, the latter being provided with a plurality of nozzles 17 and a plurality of fan blades 18. The distributor assembly forms no part of the present invention, and its operation will therefore be only briefly described. The distributor head rotates at motor speed and throws unatomized droplets of oil upwardly and outwardly, and it discharges an outwardly and downwardly extending blast of air, the streams of oil and air being combusted in a manner to be hereinafter described. The distributor assembly is adapted to be automatically controlled in accordance with temperature changes by mechanism disposed in a control stand 21.

Disposed on the upper surface of hearth 13 is a carbureting ring assembly, and in the present instance it consists of a plurality of metal segments which are welded or otherwise suitably secured together to form a unitary whole. With particular reference to Figures 2 and 3, each segment consists of a body 22 preferably of pressed metal. Although any suitable material may be employed for the segments, the high temperatures to which the metal portions of the burner are subjected necessitates the use of a special heat resisting steel unaffected by oxidizing conditions in the burner, and it has been found that a chromium steel having a chromium content of from 20 to 28% is suitable for the present device, while somewhat lower percentages of chromium may also be used with reasonable satisfaction.

Each segment 22 is provided with a vertical impact wall 23, which provides a vaporizing surface; a gutter portion 24, into which unvaporized components of the fuel may rest while they are consumed by the oxidizing atmosphere therein; and an upwardly inclined air directing surface 25. Segments 22 are supported upon the hearth by means of a plurality of metal plates 26 which generally conform to the configuration of segments 22 and are secured thereto by a welding or like operation.

Although the mechanism performs satisfactorily without them, each segment is preferably provided with a grill 28, which comprises a flanged plate having a plurality of openings 29 formed therein. Each grill 28 is secured to its segment by means of a pair of brackets 31. The forward arms 32 of brackets 31 are bifurcated 60 and straddle the vertical portions of the segment. The rear legs 33 of bracket 31 are disposed against the rear face of the segment. Brackets 31 may be welded or otherwise suitably fastened to the segments in order to make the construction more rigid if desired.

The carbureting ring assembly just described is equipped with an air deflecting, or an air redirecting assembly, and although it may take any desired form and be supported on the hearth or any other part of the burner, it is preferably mounted on the carbureting ring assembly itself and in the present instance it takes the form of a plurality of metallic members 35 which are horizontally disposed and have their ends 36 bent downwardly and welded to segments 22. Air

deflecting members 35 cooperate with the air streams projected from distributor 16 in a manner to be hereinafter described.

Combustion of the liquid fuel may be initiated in any suitable manner, the ignition mechanism of the device shown in Figure 1 taking the form of a pair of electric arcs. Preferably disposed at diametrically opposite points of the carbureting ring assembly are electrodes 37, each of which preferably consists of an intimately mixed mass of carborundum and refractory material disposed in a metallic container secured to the segments. The carbureting ring is provided with apertures opposite electrodes 37 in order to allow an arc to pass from the surface of the carborundum to an electrode 38 which is molded in the hearth opposite each electrode 37. Electrodes 38 are connected by means of leads 39 across the high side of a transformer 40. The voltage across the high side of the transformer 40 preferably lies in the neighborhood of from 12,000 to 15,000 volts and the current produced thereby goes through one electrode 38 and jumps across the gap in the form of a flaming arc, enters one electrode 37, 25 travels through the connected segments of the carbureted ring and into the other electrode, then through another flaming arc into the other electrode 38. It is therefore seen that the arcs or spark gaps are disposed in series with the result that the voltage across each gap will be one-half of the voltage across the high tension terminals.

Before proceeding to a detailed discussion of the modified forms of the invention, a description of the operation of the construction just described will now be set forth. The controlling mechanism for the burner is preferably arranged so that the motor is started simultaneously with energization of transformer 40 with the result that the oil, or other liquid fuel, is thrown outwardly from the head, (illustrated as droplets in Figure 3) and strikes portions 23 of the segment and breaks up into smaller particles which drop down into the electric arc and are volatilized and ignited. The arcs are intensely hot, and accordingly heat the volatilized fuel to a high temperature and ionize the air and oil vapor in the region of the electrodes, with the result that the vapor ignites. It should be observed that while the above operation takes place the current flowing through electrode 37 heats it to a high temperature, with the result that further atomized fuel dropping thereupon is readily volatilized.

When ignition has been initiated in the manner just described, the flame propagates around the ring in both directions thereby establishing a continuous ring. With combustion taking place around the entire periphery of the carbureting ring, segments 22 are heated, and as they are formed of relatively thin pressed metal they heat up rapidly and in a short time they attain a temperature sufficient to almost instantly volatilize the droplets of oil striking their vertical portions 23. When the carbureting ring attains a temperature sufficient to instantly volatilize the liquid fuel impinging thereagainst just described, steady combustion conditions may be said to exist in the device and at this time an automatic device of any suitable character may be employed to open the igniter circuit.

Under steady combustion conditions, the unatomized fuel emanating from head 16 takes the paths illustrated by the upper row of arrows in Figure 1, (illustrated as droplets in Figure 3)

and strike portions 23 of the segments in a line which will hereafter be termed the impingement line. The air flowing from head 16 curves downwardly as it emanates from head 16 with the result that the fuel in its passage from head 16 to the carbureting ring is isolated from the air and is accordingly incapable of burning for the reason that it is not supplied with sufficient air to form a combustible mixture. With particular reference to Figure 3, part of the air issuing from the distributor, diagrammatically illustrated by arrows A, is thrown outwardly and upwardly and mixes with the vapors generated on surfaces 23 of segments 22 and starts to burn in this region. However, as the vapors generated are in excess of the air supplied to them for proper combustion, the flame in this region is of a reducing character. A large part of the air issuing from the distributor strikes air deflectors 35 and takes the path indicated by the arrows B and mixes with the vapors in the region below the impingement line. As the amount of air in this region is in excess of that required to efficiently burn the vapors present in this region, the flame in this locality is of a highly oxidizing character. The vapor streams are illustrated diagrammatically in Figure 3 by lines C. The first described region or zone of combustion will be hereinafter termed the reducing zone and the last described region will be described as the oxidizing zone.

The gases in the reducing and oxidizing zone pass upwardly and strike grills 28 which serve to mix them, with the result that they burn above the grill with a blue flame, and the quantity of air supplied to the carbureting assembly is preferably carefully adjusted so that when the gases of the reducing and oxidizing zones are mixed, there will be just sufficient, or only a slight excess, of oxygen present above the grill to thoroughly combust all of the fuel.

Fuels of number 3 and number 4 specification, as previously pointed out, not only contain substances that cannot be vaporized, but they also contain a certain percentage of solid matter. Moreover a certain percentage of solid matter is precipitated incident to cracking of portions of the oil that is vaporized in the device.

When the burner is operating under steady combustion conditions, the solid matter in the oil, plus any solid matter precipitated incident to portions of the oil cracking under the high vaporizing temperatures existing in the segments, collect upon the surface of the segments at the line of oil impingement. This solid matter accumulates at a relatively rapid rate, depending upon the quality of the oil being burned. Nevertheless, and for some reason not clearly understood, such accumulated matter, after reaching a certain thickness, breaks into segments along its length. These segments upon being formed may drop at once to the bottom of the trough in the carbureting ring, or as is usually the case, they curl inward at their ends away from the surface of the metal until their weight acting against their weakening hold upon the impingement wall finally results in their dropping away into the trough. As previously described, the air flowing into the trough, by virtue of the air deflectors, maintains a flame therein and the relatively large amount of air causes this portion of the flame to be of a highly oxidizing character. Consequently when the solid matter breaks off and drops into this zone as just described, the combination of excess oxygen and high flame temperatures causes the rapid and complete combus-

tion of the solid matter. As the flame in the gutter is continuously oxidizing in character during normal operation of the burner, the solid or unvaporizable part of the fuel is consumed as rapidly as it forms and breaks away from the impingement wall. There is therefore no possibility of the burner becoming so incrusted with solid matter as to cause combustion to fail.

It was discovered during the course of experimentation that the high carbureting ring temperatures requisite for complete volatilization of liquid fuels of number 3 or number 4 specification causes the oil to crack into its component parts and the free carbon so released will precipitate with amazing rapidity on any convenient surface. The temperature of the collecting surface itself does not seem to influence the rate of precipitation. If anything, the hotter the surface the faster the carbon collects thereon.

Two methods of correcting this difficulty occurred at the time of developing the present apparatus; (1) provide no collecting surface until combustion of the fuel is complete or (2) maintain an oxidizing atmosphere over the surfaces in the region of the released carbon. In view of the necessity for a vaporizing surface, the second solution of the problem was followed, and the present practical apparatus resulted. Therefore it is seen that maintaining an oxidizing atmosphere adjacent the line of fuel impingement not only produces efficient and complete combustion of the solid matter in the fuel, but it also rapidly and completely oxidizes the free carbon that may be released as a result of the fuel cracking under the high temperatures encountered on the impingement surfaces.

It is important that the total volume of air introduced be not in material excess over that required to completely burn all of the fuel. The method of the present invention therefore includes directing the air in a manner to maintain an oxidizing condition in certain zones and upon certain surfaces; thereafter mixing the remaining air with its unused oxygen, the unburned vapors, free hydrogen and oxygen, and the products of combustion, in a manner to give efficient combustion of the total mass.

With reference now to Figure 4 of the drawings, there is illustrated a modified form of construction, and the only difference therein over the construction just described, resides in the shape of the air deflecting member 35a which in this instance is of curved configuration. This form of air deflecting member may be used to advantage in some installations, depending upon the volume of auxiliary air required. In fact the air deflecting member 35 of the first described construction may be adjusted or progressively bent into the curved configuration shown in Figure 4 to give the requisite balance between the air that flows directly toward the impingement line and the air that is deflected into the gutter. In view of the fact that this form of the invention functions in precisely the same manner as that just described it will not be set forth.

With reference to the carbureting ring construction shown in Figures 5 and 6, the carbureting ring assembly is provided with a series of impingement plates 41 which are provided with preferably integrally formed ears 42. Ears 42 extend rearwardly as seen in Figure 6 and are then bent downwardly to provide a vertical portion 43. Portions 43 of ears 42 are slotted vertically and are fitted over vertical portions 23 of segments 22.

This apparatus functions in a slightly different manner than those previously described in that no air deflecting member is required. Assuming that plate 41 has been heated sufficiently to substantially instantaneously vaporize the fuel striking it, vaporization takes place as previously described, and air currents A establish a reducing combustion zone adjacent the impingement line. The vapors below the line of impingement mix with air current B and establish a combustion zone in the gutter, and the products of combustion pass upwardly behind plate 41 toward the grill 28. The upward movement of the gases in this combustion zone establishes a partial vacuum in the lower part of the gutter, which results in air currents B taking the path shown and which establish an oxidizing zone. However, if desired, air deflecting members of the character shown in Figures 3 and 4 may also be used to increase the flow of air into the oxidizing zone. It should be observed that the combustion of the gases taking place behind plate 41 serves to further elevate the temperature of the vaporizing surface, with the result that vaporization of the impinging fuel is greatly enhanced. The gases passing upwardly from the reducing and oxidizing zones enter the grill where they are mixed and combusted as previously described.

With reference to Figure 7, a construction is shown that is very similar to, and functions in the same manner as that just described, but the parts are assembled in a different manner. Plate 41a at its lower end is welded to a bracket 45 which rests in a gutter 24 of the segment and is provided with a bifurcated upper end 46 which embraces the upper lip of segment 22. Segment 22 has been cut down as the impingement wall 23 is not necessary in this form of the invention. A pair of brackets 47 support grill 28, and is provided with a bifurcated end 49 which embraces the upper edge of plate 41a. Rear legs 48 of brackets 47 engage behind segments 22.

The modified carbureting ring construction shown in Figures 8 and 9 functions in the same manner as those shown in Figures 5, 6 and 7. In this form of the invention the segments are replaced by a plurality of segments 52, which are secured together in end to end relationship as those employed in the previously described forms of the invention. Segments 52 are each provided with a vertical wall 53, a horizontal base 54 and an upwardly inclined front wall 55. Plates 41b are disposed within segments 52 and are provided at their lower ends with outwardly turned tabs 56, which cooperate with the front walls 55 of the segments and inwardly turned tabs 57, which cooperate with the rear wall of the segment to maintain plates 41b properly spaced from the segment walls. A pair of U-shaped clamps 59, each having downwardly extending legs 61 and 62, is mounted upon plate 41b and the rear wall 53 of segment 52 and supports grills 28 which are welded thereto.

This form of the invention performs in precisely the same way as the apparatus shown in Figures 5, 6 and 7, a part of the air stream A passing upwardly and establishing a reducing zone in the region of the impingement line and another part of the air stream B passing downwardly within the segment and under plate 41b to establish the oxidizing zone, where the solid matter is consumed as previously described.

In Figure 10 there is illustrated a further modified construction, and in this form of the invention the carbureting assembly takes the form

of a continuous ring, as distinguished from the segments employed in the previously described forms of the invention. With continued reference to Figure 10, a plurality of bracket members 65 are disposed upon hearth 13 and have extending tabs 66 molded therein. Secured to the upper face of each bracket 65, by means of a plurality of tabs 67 which are preferably struck therefrom, is a clamp member 68 having upstanding arms 69 and 70. A ring member 71, 10 against which the fuel is adapted to impinge, is mounted on brackets 68 and is secured thereto by bending the upper ends of arms 69 thereover. A narrower ring 72 is secured to arms 70 of brackets 68. Grills 28 are secured to spaced portions of ring 71 by means of bracket members 74. An air deflecting member 76, which may be continuous or segmental in form, is secured to the upper edge of ring 72 by means of brackets 75.

In this form of the invention, air currents A 20 pass upwardly and mingle with the vapors in the region of the oil impingement line on ring member 71 and establish a reducing zone in a manner similar to that effected in the previously described constructions. Air currents B pass upwardly and are deflected downwardly by member 76 into the gutter formed between ring members 71 and 72 and establish an oxidizing zone wherein the solid or unvaporizable components 30 of the fuel are consumed. The gases emanating from the reducing and oxidizing zones pass upwardly and are mixed and consumed above the grills as in the previously described forms of the invention.

The construction shown in Figures 11 and 12 is 35 identically the same as that just described except for the air deflecting member, which in this instance is integrally formed with the smaller of the carbureting ring members. In this form of the invention ring 72a is slit horizontally along 40 edges 77 and 77' to form air deflecting members 78, which are connected to the ring at intervals by integral supporting portions 79 of the ring.

In Figures 13, 14, 15 and 16 there is shown a 45 modified form of igniting device also forming part of the present invention, and it is particularly useful in the present apparatus as it is capable of initiating combustion of the heavier fuels. The igniting device has been illustrated in connection 50 with the carbureting ring assembly shown in Figures 1, 2 and 3, and although two igniter assemblies are used only one will be described.

With particular reference to Figures 13 and 14, an aperture 80 is formed in segment 22 and a box-like member 81 is welded to segment 22 in alignment with aperture 80. Secured to a downwardly projecting finger 82 of member 81 is a clamp 83. Detachably carried by clamp 83 is an insulator 84 having an electrode 85 therein. Electrode 85 is insulated from member 81 and is provided with an enlarged upper end 86 for a purpose that will presently appear.

Insulating material 87, preferably having thermal as well as electrical insulating properties, is disposed within member 81 and against the rear face of segment 22. Molded in place within member 81 and projecting through the opening 80 in segment 22 is a mass of conducting material 89, which preferably consists of a mixture of carborundum and a refractory binder of preferably electrical insulating properties, so that when current passes therethrough it will heat up and volatilize the fuel. The lower ends of electrodes 85 are provided with terminals 90. Co-

operating with one of the electrodes 85 is a metallic hearth electrode that will now be described.

Secured to a recessed portion 91 of segment 22, as by means of a welding operation, is a clamp member 93 which is molded in the hearth and which clamps an insulator member 94 in place. Disposed within insulator member 94, and secured thereto at its lower end, is an inner insulator 95 carrying an electrode 96 which curves upwardly and outwardly and terminates in a somewhat blunt tip 97, which is disposed sufficiently close to the carborundum electrode to form an arc when a high voltage is impressed across the electrodes.

15 The transformer and electric circuit preferably employed with the igniting device is illustrated in Figure 16. The transformer has a primary winding 99 which, if the fuel burning apparatus is mounted in a residence, is connected across the regular 110 volt, 60 cycle line. The transformer is provided with two secondary windings 101 and 102. Winding 101 is connected across electrodes 86, and one end of winding 102 is connected to electrode 96. Although the transformer 20 has been conventionally illustrated, winding 101 is designed to cause a comparatively heavy current, say, 180 milliamperes to flow between the electrodes 86 with a drop in potential of approximately two thousand volts, while winding 102 is 25 designed to have a greater number of ampere turns, so as to cause a current of say 18 milliamperes to flow between electrode 97 and electrode 86.

It is accordingly seen that when the burner is 30 put into operation a heavy current flows between terminals 86 and rapidly heats member 89, with the result that when fuel particles gravitate downwardly on the hot surface of this member they are rapidly volatilized. Simultaneously an 35 arc is established between electrode 97 and member 89, which serves to further volatilize the fuel and ignite it. It should be observed that while current is passing between electrodes 86, the heat generated in member 89 is conserved by reason 40 of the insulating action of members 87, which also electrically insulates member 89 from the 45 ring segments. The heat generated in member 89 is accordingly prevented from dissipating into segments 22 and accordingly promptly reaches a vaporizing temperature.

50 As previously mentioned, the carbureting ring assembly in this form of the invention is provided with two diametrically opposite igniter assemblies and although we have illustrated each igniter assembly as being provided with a separate transformer, it is to be understood that if desired, the transformer may be made of greater capacity and be connected in series or parallel to both of the igniter assemblies.

60 With reference to all of the forms of the invention, it is to be understood that although various devices have been illustrated for deflecting or re-directing a portion of the air emanating from the distributor head for establishing an 65 oxidizing zone in the carbureting assembly, air for this purpose may be independently supplied if desired, as for instance, by means of a separate fan directing air directly to the carbureting ring gutter, and the appended claims are intended 70 to embrace the present invention when it assumes this form.

The invention may be embodied in other specific forms without departing from the spirit or essential characteristics thereof. The present embodiments are therefore to be considered in all re-

spects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a liquid fuel burning apparatus comprising a combustion chamber having a hearth and means for discharging liquid fuel in a path over said hearth, a carbureting device mounted on said hearth in the path of the discharged fuel, said device comprising an upper fuel impact wall portion, a lower wall portion and a grooved or depressed imperforate portion forming a sheltered gutter between said wall portions, means for projecting a major draft of air against said lower wall portion and across said gutter, and means for projecting a minor air draft into said gutter. 20

2. In the combination defined in claim 1, the last mentioned means comprising a member carried by said device and constructed to form said minor air draft from a portion of the air of said major draft. 25

3. In the combination defined in claim 1, the last mentioned means comprising a deflector overlying said lower wall portion and said gutter.

4. In a liquid fuel burning apparatus, in combination with a combustion chamber having a hearth and an upright wall, fuel distributing means positioned to project a liquid fuel stream toward said wall and means for directing a blast of air toward said wall, a refractory carbureting structure disposed between said wall and said 30 distributing means, said structure comprising an imperforate gutter arranged transversely of and below the projected fuel stream, a member providing an air deflecting surface in front of said gutter in the path of the air blast and positioned 35 to direct said blast upwardly, means providing a fuel impingement surface above said gutter in the path of the upwardly directed blast, and means for causing a part of the air blast to flow 40 into said gutter during operation of the apparatus. 45

5. In the combination defined in claim 4, said means providing said fuel impingement surface being thin and of good heat conductivity and disposed forwardly of the rear side of said gutter. 50

6. In a liquid fuel burning apparatus; a heat exchange unit having a combustion chamber; a liquid fuel carbureting member providing a substantially vertical surface disposed in said chamber, means for projecting unatomized liquid fuel toward said surface for atomizing said fuel by impact with said surface; means for projecting a draft of air toward said surface for admixture with the atomized fuel for establishing and maintaining a combustion zone adjacent said vertical surface between said first-named means and said vertical surface, and means for causing a part of the projected air draft to form an oxidizing zone below and adjacent to said combustion zone. 55

7. The liquid fuel burning apparatus set forth in claim 6, wherein said last named means comprises a deflecting means for diverting a part of the air supplied said combustion zone to a region below said combustion zone. 60

8. In a liquid fuel burning apparatus, a member having a substantially vertically disposed atomizing surface, means for projecting an air current and liquid fuel toward said atomizing surface, for causing said fuel to be atomized by 65

impact with said surface and to be mixed with a part of said air current and means for causing a portion of said air current to be deflected to a region below said atomizing surface.

5. 9. The fuel burning apparatus set forth in claim 8, wherein said last-named means comprises at least one air deflecting member disposed in the path of said air current.

10. In a device for burning liquid fuel, a heat exchange unit having a combustion chamber; a fuel carbureting member disposed in said chamber and providing a substantially vertically extending fuel atomizing surface and a gutter located below said surface; means for causing liquid fuel to impinge against said atomizing surface, means for causing an air current to flow past said gutter for admixture with the fuel atomized on said surface, and means for causing a current of air to flow into said gutter for combusting any fuel accumulating therein.

11. The liquid fuel burning apparatus set forth in claim 10, wherein said last named means comprises an air deflecting element mounted on said carbureting member and disposed between said atomizing surface and the source of the air supplied to the fuel atomized on said atomizing surface.

12. In a liquid fuel burning device, a liquid fuel projector, a carbureting member providing a substantially vertically disposed atomizing surface in the path of the liquid fuel discharged by said projector, means for mixing air with said liquid fuel atomizing by impact with said atomizing surface for effecting combustion of said liquid fuel, in the region of said surface impacted by said liquid fuel, and means for causing hot gases of combustion to pass downwardly under and thence upwardly with respect to said atomizing surface for simultaneously consuming any fuel

that fails to vaporize on said atomizing surface and for heating said atomizing surface.

13. In a liquid fuel burning apparatus comprising a combustion chamber having a hearth and means for discharging liquid fuel in a substantially horizontal path over said hearth, a carbureting device mounted on said hearth in the path of the discharged fuel, said device comprising an upper fuel impact wall portion, a lower wall portion and a grooved or depressed imperforate portion forming a sheltered gutter between said wall portions, means for projecting a major draft of air against said lower wall portion and across said gutter, and means for projecting a minor draft into said gutter comprising a downward extension provided on said fuel impact wall and projecting downwardly into said gutter.

14. In a liquid fuel burning apparatus, a combustion chamber having a hearth, an upright fuel impact wall disposed adjacent the periphery of said hearth, said hearth being provided with an aperture centrally thereof, a distributor mechanism projecting upwardly through said aperture and embodying means for projecting a sheet-like blast of air outwardly over said hearth toward said fuel impact wall and means for projecting solid droplets of liquid fuel against said impact wall for atomizing and vaporizing the same, means located inwardly of said impact wall for deflecting said blast of air upwardly and outwardly adjacent said impact wall, and means for deflecting at least a part of said air from its upward course comprising a plurality of thin members constructed of a metal which is resistant to destruction by heat and has good heat conductivity.
